UNITED STATES PATENT OFFICE.

THOMAS NIXON, OF SANTA BARBARA, CALIFORNIA; BLANCHE H. NIXON, ADMINISTRATRIX OF SAID THOMAS NIXON, DECEASED.

CASEMENT-WINDOW.

1,331,821.

specification of Letters Patent. Patented Feb. 24, 1920.

Application filed October 26, 1918. Serial No. 259,772.

To all whom it may concern:

Be it known that I, THOMAS NIXON, a citizen of the United States, residing at Santa Barbara, in the county of Santa Barbara and State of California, have invented certain new and useful Improvements in Casement-Windows, of which the following is a specification, reference being had to the accompanying drawings.

10 This invention relates to windows, and particularly to casement windows.

The general object of the invention is to so construct the casement window that it shall be locked against inward opening movement when the window is closed and in this connection to provide a casement window which in its normally closed position is lowered into a recess in the window sill so that it cannot be opened but which may be raised 20 a slight amount in order to disengage the two sashes of the casement window from the walls of the recess to thereby permit the sashes to be opened.

A further object is to so construct a casement window that when closed it shall prevent the entrance of water and dust.

A further object is to provide means whereby the window may be readily lifted out of the locking recess in the sill to permit 30 the window sashes to be opened.

Still another object is to provide means for holding the window sashes in a plurality of open positions.

Other objects will appear in the course of 35 the following description.

My invention is illustrated in the accompanying drawings, wherein:—

Figure 1 is a vertical sectional view of a window constructed in accordance with my 40 invention;

Fig. 2 is a vertical sectional view through the window frame, one of the sashes being in elevation;

Fig. 3 is a face view of the plate 17;

45 Fig. 4 is a fragmentary transverse sectional view on the line 4—4 of Fig. 5;

Fig. 5 is a front elevation of a window frame with the sashes closed;

Fig. 6 is a fragmentary vertical section 50 through the upper portion of the window frame, the section being parallel with the face of the window casing;

Fig. 7 is a top plan view of the sash adjusting mechanism;

Fig. 8 is a fragmentary face view of the 55 window frame; and

Fig. 9 is an elevation of one of the hanglers for the levers 30.

Referring to these figures, it will be seen that the window frame is constructed in the 60 usual manner, except that a recess is provided in the head of the frame to permit the upward movement of the window to a slight degree and a recess is provided rearward of the window stool into which the lower end 65 of the sash normally rests. The sashes consist of the usual rectangular sash frames 10 carrying the panes 11 and the hanging stile 12 to which the sash frames 10 are hinged, as at 13, the outer faces of the stiles being 70 rabbeted and the confronting faces of the sash frames being rabbeted to correspond. The outer ends of the hanging stiles are connected by means of an integral cross bar 14 which is also rabbeted to receive the upper 75 rail 10^a of the sash. The lower ends of the hanging stiles are not connected. The hanging stiles are slidingly engaged with the jambs of the window frame by means of screws 15 passing through vertically disposed slots 16 in the hanging stiles 12, the heads of the stiles being disposed in a longitudinally extending countersink formed in a slotted metallic strip 17 (see Fig. 4). The slot 18 of this strip and the slot 16 are just 80 long enough to permit a vertical movement of the hanging stile sufficient to clear the corresponding sash from the recess in the window sill. The hanging stile 12 slides against the usual blind stop 19 on the outside of the sash and the usual stop 20 on the inside of the sash.

The head of the window casing, as illustrated in Fig. 2, consists of the head 21, the false head 22, the blind stop 19 and the 95 stop 20. The sill of the window comprises the sill proper 23, the stool 24, and the center stop 25. The outer edge of the stool 24 is downwardly beveled as at 26 and the stop 25 is spaced from this inner edge a distance 100 just sufficient to permit the lower rail 10^b of the window sash to slip into place between the beveled edge 26 of the stool and the stop 25. The inner corner of this rail 10^b is beveled so as to fit against the beveled face 105 26. When this sash is lowered, this lower rail rests upon the sill 23. Between the blind stop 19 and the false head 22 there is

formed the transversely extending recess 27 of such depth that when the sashes are raised, the lower edge of the sashes will be disposed above the stool 24 so as to permit 5 the window sashes to be swung open.

For the purpose of counterbalancing the window sashes so that they may be readily lifted by hand, I hinge to the frame of the window, on each side, the hangers 28, each 10 hanger being U-shaped in form and having a pintle at its upper end engaged with the hinge leaf 29, the lower end of the hanger having pivoted thereto a lever 30, the inner end of which is notched as at 31 and extends 15 into a mortise in the hanging stile. Extending across this mortise is a metallic plate 32 held by screws to the hanging stile and with which the notched end 31 of the lever engages.

20 The lever 30 extends into the weight chamber of the window jamb and connected thereto by a wire cable 33 is the sash weight 34. The weights are about two-thirds the weight 25 of the window sash and the hanging stile so that the window sash with its stile is not entirely counterbalanced but at the same time may be readily lifted by hand.

For the purpose of locking the sashes closed and also providing means whereby 30 the sashes may be readily raised, I mount upon each lower rail 10^b of the sashes, a latch 35, the lower end of which is outwardly turned or hooked as at 36, each latch being pivotally mounted between ears 37 35 and each latch having at its upper end a projecting lug or extension 38. The stool 24 is recessed as at 39 to receive the hooked end 36 of the latch, this recess being covered by a keeper plate 40.

40 For the purpose of releasing the latch, I pivotally mount above the latch 35 an actuating and lifting member 41 which is provided with a tooth 42 engageable with the lug 38 and with the outwardly and downwardly curved finger piece 43. A spring 44 urges the latch inward into locking position. The upward movement of the member 41 is limited by the upper end of the recess 45 wherein the actuating member 41 45 and the latch are disposed, and it will be obvious that as the member 41 is pulled upward, the tooth 42 will engage the lug 38 and force the detent end 36 of the latch 35 inward and away from beneath the keeper 50 plate 40 and that then a further upward movement of the member 41 causes it to abut against the stop formed by the end of the recess so that this finger hold 43 forms means for raising the sash.

55 60 Preferably the hanging stile operates against a wooden anti-friction roller 46 disposed in a recess 47. Of course I do not wish to be limited to this, nor do I wish to be limited to any of the details of construction.

For the purpose of holding the sashes in their open position I provide an adjusting plate 48 which is sector shaped and which is attached by screws 49 to the transverse bar 14 of the hanging stiles so as to extend out just above the upper rail 10^a of the corresponding sash. The arcuate face of the adjuster plate is formed with a plurality of notches 50, this arcuate face being concentric to the centers of the hinges on which the sashes swing and I mount upon the upper rail 10^a of each window sash a spring bolt, the casing of which is designated 51. Disposed within this casing or housing is a spring actuated bolt 52 carrying at its end a roller 53 designed to engage in the notches 50, the housing or casing being slotted as at 51' to permit the retraction of the spring bolt on the roller. While normally this spring bolt will hold the sash in any adjusted position, 85 yet pressure upon the sash will cause the roller 53 to ride up on the notch with which it is engaged and the spring bolt move inward thus permitting the ready movement of the sash to any adjusted position. 90

It will be seen that a window constructed as above described is burglar-proof inasmuch as when the sashes are lowered, the sashes are held from any opening movement by the engagement of the lower bars 95 of the sashes with the stool 24 and the stop 25. Furthermore when the sashes are lowered into their locking or closed position, the beveled face 26 will have wedging engagement with the confronting beveled face 100. of the rail 10^b, thus wedging the sashes outward into tight contact with the blind stop 19 so that any rain or dust cannot enter between the blind stop and the hanging stile nor between the bar 10^b and the window stool. 105 The window may be locked in this position in any suitable manner. When the sashes are raised by means of the member 41 they may be readily swung outward and held in any adjusted position by the latching bolt 110 and adjuster plate as previously described.

While I have illustrated a form of my invention which I believe to be thoroughly effective I do not wish to be limited thereto as it is obvious that many changes may be 115 made in the detailed construction without departing from the spirit of the invention as defined in the appended claims.

I claim:—

1. A window including a window frame 120 formed to provide laterally disposed vertical guideways and transversely disposed recesses in the head of the sill, hanging stiles disposed in the guideways and having limited vertical movement therein and connected by a cross bar disposed within the transverse recess in the head of the frame, said hanging stiles being vertically slotted, screws passing through said slots and into the jambs of the window frame to thereby 130

hold the hanging stiles from movement away from the window frame and the sashes being hinged to the hanging stiles for swinging movement in a horizontal plane, 5 said sashes when closed having their lower edges disposed in the transverse recess in the sill of the frame, and the cross bar of the hanging stiles being disposed in the transverse recess in the head and having 10 vertical sliding movement therein.

2. A window including a window frame, hanging stiles connected by a cross bar at their upper ends and having limited vertical movement in the window frame, casement windows hinged to said stiles and having vertical movement therewith and having swinging movement in a horizontal plane, the window sill being formed with a transverse recess receiving the lower rails 15 of the sashes when the sashes are closed and 20

preventing opening movement of the sashes when the sashes are lowered, the side edges of the sliding stiles of the sashes being recessed, a plate extending across the upper portion of each recess, and levers extending 25 through the window frame at each side of the window, each lever at its inner end having a notch operatively engaging beneath the corresponding plate, and hangers swingingly mounted upon the window frame and 30 pivotally supporting said levers, and weights disposed in the window frame and depending from the outer ends of the levers.

In testimony whereof I hereunto affix my signature in the presence of two witnesses. 35

THOMAS NIXON.
